R. C. DIEBENKORN
PLATE OR SIMILAR ARTICLE

Des. 157,741

Filed Jan. 2, 1948

FIG. 1

FIG. 2

INVENTOR.

Richard C. Diebenkorn

BY

Harper Allen

ATTORNEY

UNITED STATES PATENT OFFICE

157,741

PLATE OR SIMILAR ARTICLE

Richard C. Diebenkorn, Atherton, Calif., assignor to Dohrmann Hotel Supply Co., San Francisco,
Calif., a corporation of Nevada

Application January 2, 1948, Serial No. 143,494

Term of patent 14 years

(Cl. D44—9)

To all whom it may concern:

Be it known that I, Richard C. Diebenkorn, a citizen of the United States, residing at Atherton, in the county of San Mateo and State of California, have invented a new, original, and ornamental Design for a Plate or Similar Article, of which the following is a specification, reference being had to the accompanying drawing, forming part thereof.

Referring to the drawing:

Figure 1 is a plan view of a plate or similar article, showing my design; and

I claim:

The ornamental design for a plate or similar article, as shown.

RICHARD C. DIEBENKORN.
